UNITED STATES PATENT OFFICE

2,606,705

APPARATUS FOR FILLING JARS

Hans Reichle, Mahopac Falls, N. Y., assignor to
Colgate-Palmolive-Peet Company, Jersey City,
N. J., a corporation of Delaware

Application June 17, 1947, Serial No. 755,149

9 Claims. (Cl. 226—95)

1

The present invention relates to mechanism for filling jars level full of a pasty or plastic material.

In my Patent Number 2,229,476, issued January 21, 1941, I have disclosed a filling mechanism capable of filling successive jars level full of a pasty or a plastic material. The present invention involves improvements in the device shown in the patent and has among its objects the prevention of leakage during filling of the jars and the selective prevention of discharge of material from any filling head in the event a jar is not in position to receive it.

Other objects and advantages will become apparent from the following description, taken in conjunction with the drawings, in which:

Fig. 1 is a side view of a filling mechanism embodying the present invention.

Fig. 2 is a fragmentary elevation along the line 2—2 of Fig. 1 with parts broken away to reveal structural details.

Fig. 3 is a fragmentary elevation along the line 3—3 of Fig. 2.

Fig. 4 is a fragmentary elevation along the line 4—4 of Fig. 5.

Fig. 5 is a fragmentary plan view with part removed to reveal details of construction.

Fig. 6 is an isometric view of a slide valve, and

Fig. 7 is a fragmentary isometric view of a portion of the valve operating mechanism.

Referring now more particularly to Fig. 1 the filling mechanism comprises a framework 1, carrying filling means 2, a jar feed mechanism 4, a jar positioning mechanism 6, valve operating mechanism 8 and a jar discharge device 10a.

Mounted on the framework 1 are bearing blocks 10 in which a rock shaft 11 is mounted. Guide rods 12 are supported at one end on the rock shaft 11 on which they are positioned by collars 13 as illustrated in Fig. 5. The other ends of the guide rods 12 are supported on a similar shaft 11a.

The material to be filled into the jars is fed to a manifold 14 from a suitable supply (not shown). The manifold has passages leading to a plurality of three-way valves (not shown) associated with reciprocating feed pumps 20 mounted at one side of the manifold 14. Reciprocating overflow pumps 21 of similar construction are mounted at the other side of the manifold 14. The piston rods 22 of the pumps 20 and 21 are connected to a carriage 23 which is reciprocably mounted on the guide rods 12 as illustrated in Fig. 1.

The feed pump 20 communicates with a filling head 24 through the feed duct 25 (see Figs. 2 and 3). The filling head also has an overflow duct 26 which communicates with the overflow pump

2

21 through a three-way valve (not shown). A slide valve 27 is slidably mounted in the filling head 24. This valve is provided in its upper surface with a recess 28 which normally connects the feed duct 25 with the overflow duct 26 as shown in Fig. 3. Valve 27 also is provided with a feed opening 29, and an overflow opening 30 separated by a bridge 31. Under the slide valve is a wiping plate 32 preferably formed of soft rubber.

In the mechanism illustrated in the drawing each filling head 24 is provided with a dual set of feed ducts 25 (see Fig. 2) and overflow ducts 26 communicating with the chamber of a single pump 20 and 21 respectively. The operation of this mechanism, which is known and forms no part of the present invention, is as follows:

The carriage 23 at the beginning of the operation is at its extreme position to the right as viewed in Fig. 1. As it moves to the left the piston rod 22 of the feed pump 20 pulls the piston toward the head of the pump and enlarges the cavity in the cylinder into the material flows from the feed supply through a three-way valve.

When the carriage has reached the limit of its movement to the left, each of the feed pumps 20 contains a quantity of the material somewhat in excess of the amount required to fill two jars.

At this time the three-way valve is turned to connect the chamber of the pump 20 with the feed ducts 25. As the carriage moves to the right the material is forced from the feed pump into the feed duct. If a jar is properly positioned and the slide valve is located so that the feed opening 29 is under the duct 25 and the overflow opening 30 is under the overflow duct 26 the material is forced into the jar under the pressure of the pump 20, until it is completely filled while the excess goes into the jar and out again through the overflow opening 30 into the duct 26. In the event a jar is not in position and the slide valve is located with the recess 28 in the position shown in Fig. 3, the charge of material intended for the jar simply flows from the feed duct 25 directly into the overflow duct 26. At the time the feed pump 20 is discharging into the duct 25, the three-way valve associated with the overflow duct 26 is turned so as to connect it with the chamber of the overflow pump 21. The piston in pump 21 is moved simultaneously to the right by its piston rod 22 which is connected with the carriage 23 so as to create a suction and prevent the material in the discharge line from building up an excessive pressure in the overflow duct 26. When the carriage 23 reaches the limit of its movement to

the right the three-way valve in the overflow line

turns so that as the overflow pump is emptying, the material in the pump is returned to the supply.

The means for reciprocating carriage 23, which are only fragmentarily illustrated, comprise a lever 33 pivoted at its lower end to the framework of the machine, a link 34 pivoted at one end to the upper end of lever 33 and operatively connected at its other end with the carriage 23, and a connecting rod 35 pivoted at one end to lever 33 intermediate its ends and cooperating at its other end with a cam (not shown) mounted on a cam shaft 36.

The jars are fed into the machine on a table 40 mounted in the framework 1. This table is provided with a plurality of slots 41, corresponding in number to the slide valves 27. A rack 42 is provided to operate in each of these slots 41. The feed mechanism per se forms no part of the present invention and it is illustrated only fragmentarily since its structure and manner of operation is well understood by those well skilled in the art. The racks 42 reciprocate to the right as shown in Figs. 1 and 3 with their teeth extending through the slots 41 so as to engage the jars on the table and move them step by step toward the right. At the end of their movement to the right, the racks are lowered until the teeth do not extend as high as the table 40, moved in unison to the left and again elevated to the starting position. The reciprocating motion is imparted to the racks by a lever 43 pivoted at its lower end to the frame of the machine and connected by the link 44 to the rack carriage. A connecting rod 45 pivoted to the lever 43 intermediate its ends cooperates with a cam (not shown) on the shaft 36 to move the rack in timed relation to the movement of the parts now to be described.

The mechanism for raising the jars from the level of the table 40 into contact with the filling heads 24 comprises an elevator bar 60 having a pair of guide rods 61 passing through suitable bearings in a fixed cross bar 62 which forms part of the framework of the machine (see Fig. 2). Collars 63 are securely fastened to each of the guide rods 61 and they carry links 64 which are pivoted respectively to one end of the levers 65, the other ends of which are pivoted to the framework of the machine, as shown in Fig. 3. A roller 66 is rotatably mounted on the lever 65 intermediate its ends. Mounted on the shaft 36 is a cam 67 having a cam groove 68 in which the roller 66 operates.

Mounted in the elevator bar 60 are a number of elevator rods 69 corresponding to the number of slide valves 27. Each of the rods 69 carries a platform 70 at its upper end. These platforms 70 in their lowermost position lie in the plane of the table 40 and are adapted to receive the front jar on the table 40 when the rack 42 is moved to the right. A collar 71 is fastened on each elevator rod 69 to limit the upward movement of the elevator rod 69 by contact with the fixed cross bar 62. A similar collar 72 is secured to the elevator rod beneath the elevator bar 60. A third collar 73 is fastened to this elevator rod 69 adjacent to the collar 71 and a helical spring 74 is interposed between the collar 73 and the elevator bar 60. This spring holds the elevator rods and associated parts in their uppermost position relative to elevator bar 60, as limited only by the collar 72, and is of such strength that when the elevator bar is raised,

a jar is held against the wiping plate 32 with only slight force.

The elevator rods and associated parts are arranged in pairs under the filling heads 24, as shown in Fig. 2. The lower ends of each pair of elevator rods 69 are connected by a yoke 75 which is pivoted thereto and connected at its center to the piston rod 76 of a fluid cylinder 77 which is pivoted to the framework 1 by pins 78. Fluid line 79 connects, through a suitable three-way valve (not shown), a source of fluid under pressure with the chamber of the cylinder 77 under the piston therein.

The mechanism for operating the slide valves 27 comprises a carriage 80 mounted to reciprocate on the guide rods 12. A cross bar 81 extends from side to side of the carriage 80 as shown in Fig. 5. Plates 82 corresponding in number to the slide valves 27 are secured to the cross bar 81 as shown more particularly in Fig. 7. A latch 83 is pivoted at one end to the cross bar 81 adjacent to the central portion of each plate 82. The other end of the latch 83 is adapted to connect detachably with the slide valve 27 by dropping into a hole 84 in the end of the valve, as shown in Figs. 3 and 6. A solenoid 85 is mounted by means of a bracket 86 above each of the plates 82 and the armature of the solenoid is pivotally connected with the latch 83 between the ends thereof.

The carriage 80 is reciprocated along the guide rods 12 by means of a pair of links 88 connected at one end with the cross bar 81 and at the other end to a crank arm 89 fastened to the rock shaft 11. The shaft is oscillated by means of a crank arm 90 which is connected to the piston rod 91 of a fluid cylinder 92 which is pivoted to the framework 1. Fluid pressure lines 93a and 93b lead from a source of fluid under pressure through suitable three-way valves (not shown) to the pressure cylinder both above and below the piston therein, as shown in Fig. 3.

A limit switch 94 is secured to the fixed cross bar 62 adjacent to each of the collars 71. This switch is in the electrical circuit of the respective solenoid 85. Each collar 71 as shown in Fig. 3, has an arm 95 rigidly secured thereto in which a screw 96 is mounted. The screw 96 can be locked in a desired position of adjustment by a locknut 97.

The mechanism for ejecting the jars from the machine after filling comprises a carriage 100 mounted for reciprocation on the guide bars 12. This carriage has an ejector bar 101 extending from side to side of the machine which is adapted to eject all the filled jars simultaneously. The carriage 100 is reciprocated through duplicate mechanisms at each side of the machine comprising a link 102 pivoted at one end to the carriage and at the other end to a lever 103 which is pivotally mounted at the lower end to the framework 1, as shown more particularly in Fig. 4. Intermediate the ends of lever 103 is mounted a roller 104. A cam 105 having a cam groove 106 is mounted on the cam shaft 36 so that the roller 104 operates in the slot or groove 106.

The operation of the machine is as follows:

With the platforms 70 in their lowermost position, the racks 42 are moved to the right, by rotation of the cam shaft 36 to deposit a jar in the proper position on each of the platforms. Further rotation of the cam shaft 36 then causes the levers 65 to swing counterclockwise and thereby raise the elevator bar 60 and all of the jar elevators comprising rods 69 and associated

parts. The parts of each jar elevator are so adjusted that when the rim of the mouth of a jar contacts the wiping plate 32 the spring 74 is slightly compressed so that the collar 71 is held a short distance away from the fixed cross bar 62. This holds the screw 96 away from the switch 94 so that the contacts are not closed. If for some reason a jar is not positioned on one of the platforms, the collar 71 travels upwardly with the associated elevator rod 69 until it contacts the fixed cross bar 62 and closes the switch 94, thus completing the electrical circuit through the respective solenoid 85, which raises the latch 83 to the dotted line position shown in Fig. 3.

As soon as the elevator bar 60 is raised to the upper limit of its movement, which presses the jars against the wiping plates 32, fluid under pressure is introduced into the cylinders 77 through the lines 79, thereby applying considerable pressure through the yokes 75 to each of the associated elevator rods 69. Simultaneously with the introduction of fluid into the cylinder 77, fluid is also introduced into the lower chamber of the cylinder 92 through line 93b, thereby swinging the crank arm 90 in clockwise direction and shifting the carriage 80 to the left. If a jar is in position on a platform 70 so that the associated switch 94 is not closed, this movement of carriage 80 slides the respective valve 27 to the left and brings the feed opening 29 under the feed duct 25. On the other hand if a jar is not in position on a platform 70, the switch 94 associated therewith is closed so that the respective latch 83 is raised to disconnect the respective slide valve 27 from the carriage 80. This leaves that valve 27 in the position shown in Fig. 3.

As soon as the carriage 80 and associated parts have reached the limit of their movement to the left, carriage 23, which in the meantime has been moved from its position at the right to its extreme position at the left, thereby charging the cylinders 29 with a supply of the material to be put into the jars, is moved to the right to discharge the material through the feed ducts 25. The pressure is maintained in the cylinders 77 during the reciprocation of carriage 23 to the right. The pressure is so regulated that each jar is held sufficiently tightly against the wiping plate 32 while the material is fed into the jar through the feed duct 25 that leakage cannot occur. As soon as the pumps 20 have been emptied, the pressure through lines 79 is released so that each jar is held against the wiping plate only by the force of the associated spring 74. Simultaneously fluid is introduced into the cylinder 92 through line 93a to return carriage 80 and the associated parts to their initial position at the right as viewed in Fig. 3.

As soon as the pressure on cylinder 77 is released, the carriage 100 is reciprocated to the right by means of the cam 105. The ejector bar 104 pushes each jar along its platform 70 while the rim of the mouth is held in contact with the wiping plate 32 by the force of spring 74 and deposits these jars on a conveyor belt (not shown) which conveys them to a capping station. As soon as the jars have been pushed beyond the platforms 70, the elevator bar 60 and associated parts are depressed by the cam 67 to their lowermost position, and carriage 100, after completing its travel to the right, is returned to its original position.

The flow of fluid to the cylinders 77 and 92 is preferably controlled by means of solenoids operating three-way valves in a conventional man-

ner and the solenoids may be energized by means of switches arranged in the path of cams mounted on the shaft 36, as those skilled in the art will readily understand.

The features of novelty in the present invention include the means for increasing the pressure of each jar against the filling head during the filling operation so that spillage does not occur and releasing this pressure so that the jar can be pushed easily along the platform in contact with the wiping plate after filling; and the disconnect mechanism for selectively preventing the operation of the slide valve in the event that a jar should not be in position to receive the charge of material.

Although the present invention has been described and illustrated in connection with the best mode of applying the principle of the invention of which applicant is now aware, modifications and variations which will accomplish the same functions in substantially the same manner are contemplated. Among such modifications and variations are the substitution of solenoids, or equivalent mechanical means for cylinders 77 and 92.

Having thus described my invention, what I claim is:

1. In filling mechanism having a stationary filling head opening downwardly and means for feeding a viscous material into a jar held against the stationary filling head, the improvement which comprises a platform adapted to hold a jar, means including a resilient connection for periodically raising and lowering said platform, and a fluid pressure device operatively connected to said platform for positively holding the jar against the stationary filling head during the filling thereof.

2. In a filling mechanism having a stationary filling head opening downwardly and means for feeding a viscous material into a jar held against the stationary filling head, the improvement which comprises resilient means for pressing the mouth of a jar against the filling head lightly and independent means for substantially increasing the pressure of the jar against the stationary filling head during filling.

3. In combination with a stationary filling head, a vertically movable jar support, a positively moved element, a resilient member connecting said jar support and element whereby the positive movement of the element is transmitted to said support through said resilient member, and independent means for applying additional upwardly directed force to said support.

4. A jar filling mechanism comprising a filling head, a slide valve therein, a reciprocating member detachably connected to said slide valve, means for positioning a jar against the filling head, a limit switch, an arm secured to said means in the path of said limit switch, said arm being so arranged that the switch is not closed if a jar is in position on said platform but is closed if no jar is in position, and means operated by closing said switch for detaching said reciprocating member from said valve.

5. A jar filling mechanism comprising a filling head, a slide valve therein, a platform below said filling head, a reciprocating member connected to said slide valve, a rod supporting said platform, a vertically movable bar having an aperture through which said rod passes, a spring urging said rod upwardly relative to said bar, a collar limiting the upward movement of said rod relative to said bar, means for moving said bar from a lower position where the platform receives a

jar to a higher position with the jar held against the filling head, and a fluid cylinder operably connected with said rod adapted to apply force upwardly when said reciprocating member opens said slide valve.

6. In a jar filling mechanism having a filling head with a sliding valve, the improvement which comprises a reciprocating carriage, a latch pivoted to said carriage and releasably connecting the carriage and valve together, a solenoid having its armature connected to said latch, a switch in the circuit of said solenoid, an elevator for positioning successive jars against said filling head, and an arm on said elevator adapted to close said switch if there is no jar on said elevator.

7. A filling mechanism comprising a filling head, a valve in said filling head, means for operating said valve having a removable connection thereto, a solenoid having its armature engaging said removable connection, a switch in the circuit of said solenoid, means for positioning a succession of jars against said filling head, an arm on said last named means in the path of said switch adapted to close the same and energize the solenoid to disconnect said removable connection if a jar is not in position against said filling head.

8. A mechanism for filling a succession of containers comprising a filling head, a valve for controlling flow of material from said head, a platform, container feed means for feeding a succession of containers to said platform, means for moving said platform from the container receiving position to and beyond a filling position, a container on said platform serving to stop the platform at the filling position by engagement with said filling head, valve control means operating in timed relation with the movement of said platform for opening and closing said valve, electrical means activated upon movement of said platform beyond said filling position in the absence of a container thereon, and means operated by activation of said electrical means for

disabling said valve control means whereby the valve is not opened if a container is not in position to receive a charge of material.

9. A mechanism for filling a plurality of containers simultaneously comprising a plurality of filling heads, a valve for controlling flow of material through each filling head, a platform movable from a container receiving position toward each filling head for positioning a succession of containers in filling position against said filling head to receive a charge of said material, container feed means for feeding a succession of containers to each of said platforms in the container receiving position, individual valve control means operating in timed relation with the movement of said platforms for opening and closing each of said valves, electrical means for detecting the absence of a container on each platform upon movement thereof toward a filling head beyond said filling position, and means operated by said electrical means for disabling said valve control means for said filling head whereby a valve is not opened if a container is not in position to receive a charge of material.
